Primary Examiner — T Chase Nelson*Assistant Examiner* — Kelly L Gross(74) Attorney, Agent, or Firm — Walter A. Rodgers(57) CLAIM

The ornamental design for a mobile spa as shown and described.

DESCRIPTION

FIG. 1 is a perspective view of a mobile spa showing my new design;

FIG. 2 is a left-side elevation view thereof;

FIG. 3 is a right-side elevation view thereof;

FIG. 4 is a rear elevation view thereof;

FIG. 5 is a front elevation view thereof;

FIG. 6 is a top plan view thereof;

FIG. 7 is a bottom plan view thereof; and,

FIG. 8 is a partial perspective view thereof.

The broken lines are included to show features of the mobile spa that form no part of the claimed design.
